UNITED STATES PATENT OFFICE.

GUSTAVE DIETE, OF CHICAGO, ILLINOIS.

DOORLOCK.

Application filed November 23, 1925. Serial No. 70,739.

My present invention relates to door locks and more particularly to locks for use on garage doors, shop doors and like places where it is desirable to make the door fast along its top and bottom edges and where it is also desirable to effect the locking engagement automatically upon moving the door into closed position, and my invention has for its main object the provision of an improved door lock of this class which will embody certain desired features of simplicity, efficiency and convenience and which will be economical in manufacture.

Other objects will appear hereinafter.

The invention consists in the combinations and arrangements of parts hereinafter described and claimed.

The invention will be best understood by reference to the accompanying drawings forming a part of this specification, and in which,

Fig. 1 represents an edge elevation of a door equipped with my improved lock, the frame parts above the door and the floor parts below the door being shown in section;

Fig. 2 is an enlarged front view of the bracket and the keeper for the top of the door, this view being taken substantially on the line 2—2 of Fig. 1;

Fig. 3 is an enlarged front view of the bracket and keeper for the bottom end of the door, this view being taken substantially on the line 3—3 of Fig. 1;

Fig. 4 is a side elevation of the parts exhibited in Fig. 3, some of the parts being shown in section;

Figs. 5 and 6 are perspective views showing garage doors equipped with my improved lock, Fig. 5 showing the doors in closed position while Fig. 6 shows one of the doors partly open;

Fig. 7 represents a section through the center piece and barrel, this view being taken substantially on the line 7—7 of Fig. 5 and showing how a common type of cylinder lock may be operatively associated with the barrel of my center piece;

Fig. 8 is a face view of the center piece and barrel associated therewith, this view being taken on the line 8—8 of Fig. 7; and,

Fig. 9 represents a face view taken on the line 9—9 of Fig. 7.

With more particular reference to the parts illustrated in the accompanying draw-

ings, 10 and 11 designate the cooperating doors of the garage 12, the doors being of any customary type hinged as at 13 for outward swinging movement and one of the doors, herein illustrated as the door 11, being furnished with a vertically extending edge strip 13 which suitably over-laps the adjacent edge of the door 10 whereby, when the doors are closed, to secure the door 10 in closed position by means of the strip 13 on door 11. In the present exemplification, therefore, my improved lock is illustrated as applied to the door 11.

The preferred embodiment of my invention as illustrated in the accompanying drawings, comprises a center piece 14 having a base flange 15 and a centrally projecting boss 16. This center piece is provided with a central bore 17 offset intermediate its length to provide a shoulder 18. Turnably fitting the bore 17 is a barrel 19 which is made with a shoulder 20 adapted to butt against the shoulder 18 so as to prevent the removal of the barrel in a direction out through the boss 16. Said barrel 19 has a part 21 which protrudes beyond the extremity of the boss 16, and this protruding part is provided with a diametrical aperture 22. The barrel 19 also protrudes for a distance beyond the base end 15 of the center piece; and extending inwardly through this protruding part, which is designated by 23, is an opening 24 which is preferably of angular form in cross section for a reason 90 presently to appear.

The center piece 14 is applied to the inner face of the door 11 along the free edge thereof and midway the distance between top and bottom ends of the door, the center piece 95 being applied by placing the base flange 15 flat against the inner face of the door and fitting the protruding barrel portion 23 into a suitable opening 24 provided transversely through the door 11, and, as herein illustrated, through the lapping edge strip 13'. The center piece is rigidly secured to the door by means of screw elements 25.

The barrel 23 of the present invention may be operated from the outside of the door by any suitable means; but the same has been especially designed for use in connection with a lock 26 of the cylinder type, having a key operated rotatable barrel 27 with which is associated a projecting bar 28. The lock 26 is applied in the usual way to the door 11 with the rotatable barrel seated

in the bore 24' and the bar 28, which is of square formation in cross section, interlocking with the barrel opening 24. By this arrangement the barrel 19 of the center piece 5 is connected with the key operated barrel 27 of the lock, whereby the barrel 19 will be rotated with the rotation of the barrel 27. A flexible member 29 in the form of a chain is taken through the opening 22 of the barrel 10 19 and is made fast to said barrel by means of a pin 30 arranged therein so as to engage one of the links of the chain. One end of this chain is attached to a latch 31 pivoted on a pin 32 arranged in the opposed lugs 34 of a bracket 35 which is secured by means of screw elements 36 adjacent the top edge of the door 11. The latch 31 is provided with teeth 37 adapted to interlock with similar teeth provided on a keeper or catch 38 20 which is suitably secured to the overhead framing or wall 39. The latch 31 is normally urged into position for engagement with its keeper by means of a pull spring 40 which has one end secured at 41 to the base of the bracket and the other end secured at 42 to the inner end of the latch at a point inwardly of the pin 32. The opposed lugs 34 are connected by a back piece 43 which serves as a stop against which the 25 latch abuts under the influence of the spring 40. The pin 32 serves as a horizontal axis for the latch so that when the barrel 19 is turned causing the chain 29 to wind on the protruding portion 21, the latch 31 will be 30 withdrawn from its keeper.

The opposite or lower end of the chain is attached to a drop latch 44 movable on a pin 45 arranged on lugs 46 provided on a bottom bracket 47 attached at the bottom 40 edge of the door. The latch 44 is provided with teeth 48 adapted to interlock with correspondingly formed teeth on a keeper 49 which is secured to the floor-board 50 below the door. The bracket 47 has a back piece 45 51 which serves as a stop to limit the downward movement of the latch 44. As in the previous instance, the latch 44 is withdrawn from its keeper when the chain 29 is turned upon the protruding portion 21 under the 50 turning movement of the barrel 19.

To open the door 11, the barrel 27 of the cylinder lock is operated by a key in the usual way with the result that the barrel 19 is turned and the chain winding on the protruding portion 21 withdraws both the top and bottom latches from their keepers. If the door is to be opened from the inside, it is only necessary to pull the chain towards the barrel 19 or to turn the barrel 19 from the inside, either of which actions results in the withdrawal of the latches from their keepers. When the door is closed the latches 31 and 44 automatically interlock with their keepers; the top latch 31 being normally held 60 65 in position by the spring for engagement

with its keeper while the bottom latch 44 drops of its own weight into position for engagement with its keeper. Both the top and bottom latches with their keepers are provided with suitable cooperating cam 70 edges 52 and 53 to enable the latches to interlock with their keepers when the door 11 is closed.

While I have illustrated and described the preferred form of construction for carrying my invention into effect, this is capable of variation and modification without departing from the spirit of the invention. I, therefore, do not wish to be limited to the precise details of construction set forth, but 80 desire to avail myself of such variations and modifications as come within the scope of the appended claims.

Having described my invention, what I claim as new and desire to secure by Letters 85 Patent is:

1. A door lock of the kind set forth comprising a key operated lock, an axis barrel controlled by said key operated lock and having a diametrical opening; latch means 90 for the door; and a flexible element extending intermediate its length through the diametrical opening of said axis barrel and attached to said latch means, substantially as described.

2. A door lock of the kind set forth comprising a key operated lock; an axis barrel controlled by said key operated lock; a pair of latches arranged to interlock with keepers; and a flexible element extending 100 through said axis barrel and therewith turnable and connecting said latches, substantially as described.

3. In a door and in combination, a lock provided with a key operated barrel; a 105 center piece; a barrel having turning fit in said center piece and extending therethrough; an operative connection between the center piece barrel and the key operated barrel whereby to operate the former from the latter; top and bottom brackets attached to the door; latches pivoted to said bracket; and a flexible element extending through said barrel and attached at its opposite ends to said pivoted latches, substantially as 115 described.

4. In combination with a door and a floor-board; of a barrel having rotatable support in the door and protruding therefrom; a bracket attached near the free edge of the 120 door; a latch pivoted to the bracket and adapted to interengage with a keeper; and a chain connected to the protruding end of said barrel and therewith turnable and attached at one end to said latch, substantially 125 as described.

In testimony whereof I have signed my name to this specification.
